UNITED STATES PATENT OFFICE

JOHN P. GRIMLEY, OF HARRISON, NEW JERSEY, ASSIGNOR TO SAMUEL J. RAWLINGS,
OF KEARNY, NEW JERSEY

DOOR-HOLDING DEVICE

Application filed November 26, 1929. Serial No. 409,904.

This invention relates to improvements in door holding devices, particularly door holders of the overhead type.

The primary object of the present invention is to provide an automatic overhead door holder which will be efficient and of a construction which makes it possible for it to be mounted in the upper part of a door opening without being in the way.

10 Another object of the invention is to provide a door holder employing a pair of arms pivotally connected one being pivotally attached to a door frame with the other pivotally attached to a door, wherein one of the 15 arms is so formed that a portion thereof will be brought to a position substantially parallel with a face of the door when the door is opened where it may be engaged by a latch member secured to the door face.

20 Another object of the invention is to provide in a door holder an improved bar engaging latch which may be set so that when the door is swung open it will automatically receive and hold a brace bar and when set in 25 another position will permit the door to be swung open or closed without locking the brace bar between the door and its frame.

The invention will be best understood from a consideration of the following detailed description taken in connection with the accompanying drawing forming part of this specification, with the understanding, however, that the invention is not confined to any strict conformity with the showing of the drawing 35 but may be changed or modified so long as such changes or modifications mark no material departure from the salient features of the invention as expressed in the appended claims.

40 In the drawing:

Figure 1 shows the device embodying the present invention in plan and in applied position.

Figure 2 is a view of the holding device in 45 elevation, a portion thereof being broken away.

Figure 3 is a sectional view taken on the line 3—3 of Figure 1.

Referring more particularly to the drawing 50 wherein like numerals of reference indi-

cate corresponding parts throughout the several views, the numeral 1 indicates a portion of a door frame into which may be swung upon the hinges 2 a door 3.

The overhead holding device embodying the present invention comprises a pair of brace bars or links 4 and 5, the link 4 being straight as shown while the link 5 is bent intermediate its ends forming an obtuse angle. As shown in Figure 2 the bars are relatively thin and are preferably formed of wrought steel so that they will have great strength without undue weight. The bars 4 and 5 are pivotally connected as indicated at 6 and the other end of the bar 4 is positioned between the side portions 7 of a substantially U-shaped bracket member indicated as a whole by the numeral 8. One of these side portions of the bracket member is widened at its free end to form the plate 9 which has apertures therein for the reception of securing screws 10 by means of which it may be secured to the top portion 11 of the door frame.

Mounted upon the inner face of the door 3 is an elongated plate 12 which has projecting therefrom adjacent one end a pair of spaced ears 13 between which the other end of the link 5 is pivotally held by the pin 14. The link 5 is so disposed with relation to the door 3 that when the door is swung open as shown in Figure 1 that angled portion of the bracket 5 which is connected to the plate 12 moves to a position substantially parallel with the face of the door. This portion of the link 5 has an aperture 15 formed therethrough adjacent the bend in the link and when the door is swung open to the position shown this apertured portion moves into a recess 16 formed transversely of the upper end of a sleeve 17 which is cast integral with a block 18 secured to the face of the plate 12, the sleeve being maintained in vertical position as shown.

At its lower end the sleeve is slightly reduced as indicated at 19 to snugly receive a latch bolt 20 the upper end of this pin carrying a head 21 which has its top face cut at an oblique angle as indicated at 22. Beneath and between the head 21 and the restricted 95

lower portion of the sleeve a spring 23 is positioned which normally tends to force the pin upwardly in the sleeve so that the angled top face of the head 21 will position in and across the slot 16. A pin 24 is carried by the bolt 20 and limits its movement upwardly by contact with the lower edge of the sleeve 17 when the bolt is in one position or by engagement in a notch 25 formed in the lower edge of the sleeve when the bolt is in another position. The lower end of the bolt carries the pair of oppositely disposed arms 26 to facilitate grasping the same so that it may be pulled down against the tension of the spring 23.

When the device is desired for use to maintain the door in open position the handle members 26 of the bolt are grasped and the bolt rotated until the pin 24 moves into the slot 25. This permits the head 21 to move up to a position where the inclined upper face thereof extends across the slot 16. When the door 3 is then swung open the pivotally connected links 4 and 5 will separate to the position shown in Figure 1, that portion of the link 5 nearest the door swinging into a position parallel with the door and into the slot 16, engaging the head 21 of the bolt and forcing the same down until the opening 15 in the bar is brought into alignment with the interior of the sleeve whereupon the bolt will spring up and lock the links in position. Upon pulling down on the bolt 20 the link 5 will be released and the brace will be easily broken upon the application of a pull to the door, the angular formation of the link 5 being such that the attached end of the link 4 will be immediately swung away from the door so that the two links may smoothly fold one over the other to permit the door to be closed. When the door reaches completely closed position the link 4 will engage the back part of the U-shaped portion of the bracket 8 limiting the movement of this link.

From the foregoing description it will be readily seen that the door holder embodying the present invention will function efficiently to secure a door in the desired open position and that it may be economically constructed.

Having thus described my invention, what I claim is:

1. A door holder comprising a pair of pivotally connected links, one thereof being bent intermediate its ends forming an obtuse angle, means for pivotally securing the free end of the angled link to a door, means for pivotally securing the free end of the other link to a door frame, said angled link being so disposed with relation to said door as to bring the angled portion adjacent thereto into substantially parallel relation therewith when the door is opened, said last mentioned portion of the angled link having an aperture formed therethrough adjacent the angle in the link, a spring pressed bolt mounted upon the door adjacent the pivotal connection

therewith of the angled link for engaging in said aperture when the door is swung open, a handle having a stem rigid with the bolt for axially rotating the same when shifted longitudinally against the spring, and means for securing the bolt against return movement. 70

2. A door holder comprising a pair of pivotally connected links, one thereof being bent intermediate its ends forming an obtuse angle, means for pivotally securing the free end of the angled link to a door, means for pivotally securing the free end of the other link to a door frame, said angled link being so disposed with relation to said door as to bring the angled portion adjacent thereto into substantially parallel relation therewith when the door is opened, said last mentioned portion of the angled link having an aperture formed therethrough adjacent the angle in the link, a transversely slotted sleeve mounted vertically on the door adjacent the point of connection therewith of the angled link designed to receive in the slot thereof the apertured portion of the angled link, a bolt 75 80 85 90 95 100 105 110 115 120 125 130

slidable in said sleeve and having a head with an inclined top surface adapted to extend into the slotted portion of the sleeve, a spring housed in the sleeve and surrounding the bolt and normally urging the bolt upwardly, and a pin member carried by the bolt for maintaining the same in a desired position.

In testimony whereof I hereunto affix my signature.

JOHN P. GRIMLEY. 100
